UNITED STATES PATENT OFFICE.

LOUIS V. ENGLAND, OF LAREDO, TEXAS.

SELF-STROPPING SAFETY RAZOR.

Application filed September 20, 1922. Serial No. 589,394.

To all whom it may concern:

Be it known that I, LOUIS V. ENGLAND, a citizen of the United States, residing at Laredo, in the county of Webb and State of Texas, have invented new and useful Improvements in Self-Stropping Safety Razors, of which the following is a specification.

This invention relates to razors, particularly those of the safety type, and has for its object the provision of a safety razor of novel construction which is provided with means whereby a strop may be associated therewith for the purpose of stropping or sharpening the edges of the blade when necessary.

An important object is the provision of a razor of this character which is provided with novel means whereby the blade may be clamped between the blade guard and be forced into a curved shape which will greatly facilitate shaving.

Another object is the provision of a razor of this character which is provided with a novel device which is detachably associated therewith and with which is also associated a strop which may be pulled back and forth subsequent to the suspension of the razor from a suitable support, the back and forth movement of the strop resulting in bringing the same into engagement with the edges of the blade alternately for effecting the sharpening action, automatic means being provided for tilting or rocking the blade during the stropping action so as to positively eliminate any danger of cutting the strop.

An additional object is the provision of a razor of this character which will be very simple and inexpensive in manufacture, easy to control and use, highly efficient in service, positive in action and a general improvement in the art.

With the above and other objects and advantages in view, the invention consists in the details of construction to be hereinafter more fully described and claimed, and illustrated in the accompanying drawings in which,

Figure 1 is a front elevation of my device showing it in shaving position.

Figure 2 is a side elevation thereof.

Figure 3 is a longitudinal sectional view.

Figure 4 is a front elevation with the blade and blade guard entirely removed.

Figure 5 is a longitudinal sectional view with the guards shown in raised position and the blade as initially inserted.

Figure 6 is a side elevation showing the strop associated therewith.

Figure 7 is a front elevation of one of the stropping members.

Figure 8 is a cross section therethrough. 60

Figure 9 is a detail view showing certain of the parts disconnected and

Figure 10 is a detail view of one of the blade holders.

Fig. 11 is an elevation of the blade used 65 in applicant's razor.

Referring more particularly to the drawings I have shown my razor as comprising an elongated hollow handle 10 which has its upper end carrying a frame 11 which in-

cludes spaced parallel arms 12 terminating in extensions 13 between which are journaled upper and lower rollers 14 and 15 respectively. One end of the lower roller 15 is provided with gear teeth 16 meshing with an interrupted gear 17 formed on one of a pair of blade holders 18. These blade holders 18 consist of short sections of round rods formed with slots 19 for the reception of the ends of the blade to be described. The blade 80 holders 18 are journaled through the sides 12 of the frame and the blade holder which is not provided with the interrupted gear is also slidably mounted through the side of the frame and is normally held in a certain position, that is its innermost position by means of a spring 20. Journaled upon the sides 12 of the frame below the blade holders 18 are short rollers 21 for a purpose to be described. 85

The numeral 22 designates the blade 90 which is of rectangular formation and which is formed centrally of its end edges with preferable semi-circular cut-out portions or recesses 23 and which is formed in the same edges but near the corners with rectangular recesses or notches 24. This blade is designed to be engaged within the slot 19 of the blade holders 18, the semi-circular cut-out portions 23 being engaged upon the slotted portions of the blade holders. It 100 should be stated that the sides or extensions 12 of the frame are formed above the blade holders 18 with arcuate slots 25 within which are engaged or rather through which are movable extensions 26 formed on the blade holders for a purpose to be described. The edge portions of the sides 12 of the frame 11 are formed with substantially L-shaped slots 26 for a purpose to be described. 105

Slidable longitudinally within the tubular handle 10 is a plunger 27 having a knurled head 28 constituting a finger grip engageable by the operator whereby the 5 plunger may be moved longitudinally and this plunger may be held in any desired position by means of a spring pressed button structure indicated at 30. Pivoted at 31 upon the upper end of the plunger and located 10 within the frame 11 is a blade guard which consists of duplicate leaves 32 formed at one edge with knuckles 33 and formed at the other edge with guard teeth 34. The 15 opposite edges of these teeth 32 are formed with small lugs 35 which slidably engage within the L-shaped slots 26. Also formed upon the outermost corners of the guard leaves 32 are hooks 36 which are so disposed as to engage the notches or recesses 20 24 in the edges of the blade 22.

In the use of the device as a razor, the blade 22 is engaged with the blade holders 18 by inserting the notched portion 23 within the slots 19 of the blade holders, the 25 spring 20 at one blade holder permitting longitudinal outward movement thereof so as to engage the edge of the blade, after which the spring 20 will operate to return the blade holder to its innermost position 30 so that both blade holders will be engaged upon the blade itself. This is done while the plunger 28 is at its lowermost position so that the leaves 32 of the blade holder will be out of engagement with the blade. 35 The operator then presses the plunger upwardly whereupon the leaves 32 of the blade guard will slide upwardly with the lugs 35 passing along the L-shaped slots 26. When this is done the hooks 36 on the 40 guard leaves will enter the notches or recesses 24 in the edges of the blade so that when the plunger is subsequently again moved to its highest position with the head 28 engaging against the open end of the 45 handle the engagement of the hooks 36 with the blade will cause the blade to be bowed into an arcuate shape as clearly shown in Figure 2 of the drawings. The device is then quite ready for use as a razor and is 50 applied to the operator's face in the usual manner. In removing the blade the reverse operation is of course followed and it will be readily apparent that it is a very simple matter to insert and remove the blade when 55 such is necessary.

In order to effect stropping of a blade when desired I make use of a U-shaped frame 40 which is provided centrally of its bight portion with a suspension ring 41 60 which may be engaged upon any suitable support such as a nail, coat hook or the like. Journaled in this frame is a roller 42 and formed at the free ends of the arms are hooks 43 of L-shape which are designed to 65 be sprung into the slots 28 in the sides 12

of the frame 11 of the razor structure. By this means it will be seen that the frame 40 is quickly and easily associated with the frame of the razor. I also make use of a stop 44 which has one end inserted between the rollers 14 and 15 of the razor structure and which has its other end passed under the short rollers 21, the intermediate portion of the strop being passed about the roller 42 of the frame 40. The operator then suspends the razor and the frame by means of the suspension hook 41 and grasping the ends of the strop pulls first in one direction and then in the other. When this is done it is apparent that the engagement of the strop with the roller 15 will cause the gear on the latter which meshes with the interrupted gear 17 on one of the blade holders to operate to turn or tilt the blade holder and consequently the blade so that the opposite edges thereof will be brought into the engagement with the strop during the movement thereof in alternate directions. It is apparent that the engagement of the extensions on the blade holders within the arcuate slots 25 in the frame of the razor will permit the necessary tilting action without any danger of the edge of the blade cutting the strop.

From the foregoing description and a study of the drawings it will be readily apparent that I have thus provided a simply constructed and consequently inexpensive safety razor in which the blade may be quickly and easily removed and replaced when it is necessary, the device being furthermore provided with an easily operable stropping means which will effectually operate to strop both sides of the blade in a very rapid and efficient manner and with the expenditure of a minimum degree of time and labor. Owing to the simplicity of the construction and the fewness of the parts it is apparent that there is nothing to get out of order and that the device should consequently have a long life and satisfactorily perform all the functions for which it is intended.

Having thus described the invention I claim:

1. A razor of the character described comprising an elongated hollow handle, a frame mounted upon one end of the handle and formed with extensions, a pair of spaced rollers journaled through said extensions, a gear on the end of one roller, a pair of blade holders rotatably mounted within said frame, gear teeth formed on one of said blade holders and meshing with said gear, one of said blade holders being longitudinally movable and invertedly spring pressed, a blade engageable within said blade holders, a pair of rollers located below said blade holders and journaled in the frame, a plunger slidably longitudinally of 120 125 130

- said handle, a blade guard formed at hingedly connected sections carried by said plunger and provided with means for engaging the blade whereby to hold the same in closed position, in combination with a frame detachably connected with said first named frame and carrying a roller and suspension means, and a strop trained about said last named roller and having one end inserted through said first named rollers with the other end engaged beneath said last named rollers in the frame.
2. A razor comprising an elongated hollow handle, a U-shaped frame carried by one end of said handle, a pair of slotted blade holders mounted within said handle, one of said blade holders being slidable whereby to be returned from the frame, a spring normally urging said movable blade holder, a blade having its intermediate portion of its opposite end notched for engagement within the slots of the blade holders, the edges of said blade being furthermore formed with recesses, a plunger slidable longitudinally of the handle, means for holding said plunger in selected positions, and a blade guard consisting of a pair of similar leaves hingedly connected and carried by the upper end of said plunger, said leaves being provided with hooks engaging within the notches in the blades, and the plunger being movable whereby to bow said blade into arcuate form.
3. A razor of the character described comprising a handle, a frame carried thereby and formed with extensions, a pair of rollers journaled between said extensions, the side of said frame being formed with L-shaped slots, a blade located within the frame, a rotatable support for the blade, a guard for the blade, in combination with a U-shaped frame having a roller mounted therein and provided with L-shaped lugs fitting within said L-shaped slots, and a strop having one end engaged between said first named rollers with its intermediate portion engaged about said last named roller and its other end engaging about a third roller journaled within the frame.
4. A razor of the character described comprising a handle, a frame carried thereby and formed with extensions, a pair of rollers journaled between said extensions, the side of said frame being formed with L-shaped slots, a blade located within the frame, a rotatable support for the blade, a guard for the blade, in combination with a U-shaped frame having a roller mounted therein and provided with L-shaped lugs fitting within said L-shaped slots, and a strop having one end engaged between said first named roller with its intermediate portion engaged about said last named roller and its other end engaging about a third roller journaled within the frame, the blade holding means having an operative connection with one of said first named rollers whereby to swing the blade holders and consequently the blade alternately to one side and then the other as said strop is moved longitudinally in opposite direction.

In testimony whereof I affix my signature.

LOUIS V. ENGLAND.
